UNITED STATES PATENT OFFICE.

WILLIAM B. MOSES, OF BROOKLINE, MASSACHUSETTS.

ELECTRICAL APPARATUS.

1,391,967.

Specification of Letters Patent. Patented Sept. 27, 1921.

Application filed March 6, 1917. Serial No. 152,542.

To all whom it may concern:

Be it known that I, WILLIAM B. MOSES, a citizen of the United States, and resident of Brookline, in the county of Norfolk and State of Massachusetts, have invented certain new and useful Improvements in Electrical Apparatus, of which the following is a specification.

This invention relates to electrical apparatus for use with internal combustion engines, and with regard to certain more specific features thereof to electric starting, ignition and generating systems and circuit controlling devices therefor.

10 The invention has for one of its objects to provide a simple and compact circuit controlling device for use in connection with electrical systems of the character above mentioned.

15 Another object of the invention is to provide a reliably operative automatic switch which shall be durable and inexpensive to manufacture.

Another object of the invention resides in the provision of a conductor having a thermostatic characteristic, which conductor is adapted to serve as an automatically operative latch for holding the contacts of the generator, battery and ignition circuits in closed position until released manually or under the influence of abnormal current flow. The combination of such a conductor or thermostatic latch with a switch carrier and means of simple and compact construction for temporarily making a starting motor circuit and simultaneously insuring against a closed generator circuit is still another feature of the invention.

In systems of the character mentioned it is usual to employ a storage or secondary battery from which the electrical energy is supplied to the starting motor to give the engine its initial compression. The battery may also be used to operate the ignition device or a magneto may be used for this latter purpose. The present invention has an important application to a system employing battery ignition and another of the objects of the invention is to safe-guard the battery and other delicate appliances and protect the whole against accidental or unnecessary discharge of the battery.

Other objects will be in part obvious and in part pointed out hereinafter.

The invention accordingly consists in the various features of construction, combinations of elements and arrangements of parts which will be exemplified by the construction hereinafter set forth and the scope of the application of which will be indicated in the following claims.

In the drawings wherein are shown two of various possible embodiments of the invention,

Figure 1 is a sectional view of the circuit controlling device embodying the invention. An electric starting, generating and ignition system being shown in connection therewith in schematic form (the circuit controlling device being shown in so-called "off position").

Fig. 2 is the same as Fig. 1 except that the parts of the circuit controlling device are shown in so-called "starting position."

Fig. 3 is the same as Fig. 1 except that the parts of the circuit controlling device are shown in so-called "running position."

Figs. 4, 5, 6 and 7 show different views of the circuit controlling device.

Fig. 8 is a view of a modification of the invention showing its application to a system employing magneto ignition.

Referring now more particularly to the drawing wherein similar reference characters refer to similar parts throughout the several views there is indicated at 1 a terminal block or casing which in the battery ignition embodiment of the invention shown in Figs. 1, 2 and 3 contains four terminals numbered respectively 2, 3, 4 and 5. The terminal block 1 is housed by a casing 6 and a cover plate 7; the latter being provided with suitable means 8 for attaching the whole structure to the dash of an automobile or to any suitable panel. In electrical connection with terminal 2 is a yieldable contact 9 and electrically connected with terminal 3 there is a contact 10. The terminal 4 carries a contact finger 11 which is slightly yieldable and which is adapted under normal conditions to engage with a contact 12 which in turn is electrically connected with terminal 5. The contact 12 is one portion of a standard or up-right 13 of brass or steel or other suit-

able conducting metal and secured to the upper end of this standard 13 is a pin 14, also of conducting materials coiled around this pin 14 and with one end secured therein 5 is a thermostatic device 15 constructed of two strips of metal having different relative expansions under the application of heat. These two strips are electrical conductors, such for instance as steel and brass welded 10 together with the steel strip on the outside of the coil in order that the depending or free end 16 will tend to flex or warp outwardly as the heating increases. The free end 16 of the coil 15 carries a contact pin 17 15 adapted to engage with certain movable contacts in a manner which will more fully hereinafter appear.

Within the casing 6 there is provided a movable contact-carrying member 18 20 equipped with a push button 19 by which it may be manually operated from the off position shown in Fig. 1 to the starting position shown in Fig. 2. This movement takes place against the action of a spring 25 20 coiled around a stem 21, which has its lower end journaled in a bore 22 in the terminal block 1. The push button 19 is preferably of cylindrical form and protrudes through a circular aperture 23 in 30 the cover plate 7, the latter serving somewhat as a guide or bearing and coöperating with the terminal block to support and guide the contact-carrying member 18. The body portion 24 of the member 18 is of conducting material and is provided with a knife contact 25 adapted to engage the fixed contact 10 when the device is in starting and running positions. A flat contact portion 26 is also formed on the body 24 of the member 18 and this portion is adapted to engage with the flexible contact 9 when the device is in starting position as shown clearly 40 in Fig. 2 of the drawings. In addition to the two contacts 25 and 26 of the member 18 45 there is a conducting arm 27 having a contact portion 28 with which the pin 17 of the thermostatic device 15 is adapted to engage when the device is in running position. It is also desirable that the contact pin 17 50 should have electrical communication with body 24 of the member 18 when the device is in starting position and to this end there is provided a flexible contact strip 29 attached to and in electrical communication 55 with the conductor arm 27. A block 30 of insulating material is secured on the under side and end of the conductor arm 27 and this block is formed with a lower cam face 31 and an upper cam face 32. It will 60 be noted that when the parts are in off position as shown in Fig. 1 the block 30 assumes a position with its cam face 32 somewhat above pin 17, so that the latter rests against cam face 31. In fact the pin 17 65 bears with some pressure against this cam

face 31 due to the original condition of flex of the coil 15, which when lax causes pin 17 to rest in a vertical plane with the contact 28 substantially as shown in Fig. 5 of the drawings. Manually operative means are 70 provided, comprising a small push button 33, and a link connection 34 between this button and the pin 17, whereby the operator may disengage contacts 17 and 18 at will.

The circuits and electrical devices are as 75 follows: A storage battery is indicated at 40, a starting motor at 41; a generator is provided as indicated at 42 to recharge the storage battery and furnish the current for lights and ignition and an ignition device 80 is represented generally at 43 with its coil at 44. An automatic or magnetic switch is shown at 45 arranged in the starting circuit.

The operation of the apparatus is as follows: From the position shown in Fig. 1 85 the operator by a movement of the push button 19 causes the contact-carrying member 18 to move inwardly to bring the contacts 9 and 26 into engagement. This closes an electrical circuit from the storage battery 90 40 to ground through the conductor 46, coil 47 of the automatic switch, conductor 48, terminal 2, contacts 9 and 26, body 24, contacts 25 and 10, terminal 3, conductors 49 and 50 to the negative side of the battery. 95 The energization of the solenoid 47 bridging the contacts 51 and 52 of the switch completes a circuit from the battery through the starting motor through the automatic switch, conductors 53 and 50 to battery 100 whereupon the starting motor operates to set in motion the internal combustion engine (not shown).

It will be apparent that the inward movement of the contact-carrying member to the 105 starting position shown in Fig. 2 carries the insulating block 30 to its lower-most position allowing the spring pressed contact 17 to ride over the cam faces 31 and 32 into engagement with the contact 29.

In this manner an electrical circuit is established through the ignition device substantially simultaneously with the energization of the starting motor. The ignition circuit is from battery to ground through 110 the conductor 60, primary coil 61, interrupter 62, conductor 63, terminal 5, contact 12, upright 13, pin 14, thermostatic conductor 15, contact pin 17, contact finger 29, body 24 of the contact-carrying member, 120 contacts 25 and 10, terminal 3, conductors 49 and 50 to negative battery.

It is to be noted that the insulating block is provided with a nose 70 which in the inward or downward movement of the contact-carrying member to the starting position engages the contact finger 11 to push it out of engagement with contact 12. This opens the generator or charging circuit during the starting operation. The engine hav- 130

ing started, the operator removes his hand from the push button 19 allowing the spring 20 to act upon the member 18 to restore it toward its original position; full return of the same is prevented, however, by the spring action of the thermostatic device 15, the pin 17 being at this time in engagement with contact 28 of the conductor arm 27. Member 18 therefore returns substantially to the position shown in Fig. 3 of the drawings where it is held until such time as the operator may push the button 33, or the thermostatic device may be operated by high current values to automatically move outwardly over cam face 32.

Fig. 3 of the drawings shows the running position. The automatic switch circuit having been opened at contacts 26 and 9 the motor circuit is deenergized. The ignition circuit remains substantially the same except that said circuit may be closed through either the contact 28 or the contact 29. The generator circuit is from the positive brush of the generator to ground to battery through conductor 50 and 49, terminal 3, contacts 10 and 25, member 18, conductor arm 27, contacts 28 and 17, thermostatic coil 15, pin 14, upright 13, contacts 12 and 11, terminal 4, conductor 75 back to generator.

Assuming now, for instance, a stalled condition of the engine, the storage battery 40 will immediately tend to discharge through the generator or ignition device or one or both of them at that time in a closed circuit including the thermostatic coil 15. This higher or abnormal current value in the coil will cause rapid heating of the metals contained therein and the expansion of the brass 40 being greater than that of the steel and the steel being on the outside of the coil, the lower or free end 16 of the coil will warp or flex outwardly toward the casing over the cam face 32 of the insulation block 30 45 to a point where it is free and clear of the entire block. The spring 20 will then instantly return the contact-carrying member with all of its contacts and appurtenances to its original or off position shown in Fig. 50 1. It is pointed out that the same effect may be obtained by the operator pushing inwardly on the button 33 as the link 34 is yoked around the pin 17. It will be apparent that there are conditions other than that 55 of a stalled engine which would cause the thermostatic switch to operate.

In the modifications shown in Fig. 8 the construction is substantially the same for the battery, starting switch and starting 60 motor circuits; in this instance, however, it is expected that a magneto will be used for ignition purposes and a nose 77 is provided on an insulating block corresponding to the block 30 which in the operative position of 65 the apparatus holds contacts 78 and 79 out

of engagement. When the thermostatic switch operates in this case to permit the spring 20 to restore the parts to their original position the contacts 78 and 79 will close short circuiting the magneto.

As many changes might be made in the above construction and as many apparently widely different embodiments of this invention might be made without departing from the scope thereof, it is intended that all 75 matter contained in the following description or shown in the accompanying drawings shall be interpreted as illustrative and not in any limiting sense.

Having described the invention what I 80 claim is:

1. In apparatus of the character described, in combination, an ignition device for an internal combustion engine, a generator, an electric circuit including said ignition device and said generator and having means other than said generator for supplying current to said ignition device, and a thermostatic device in circuit adapted to be influenced by predetermined current values to 90 automatically alter the operative condition of said circuit, and means for manually effecting such alteration in circuit conditions.

2. In apparatus of the character described, in combination, an ignition device for an 95 internal combustion engine, a generator, an electric circuit including said ignition device and said generator and having means other than said generator for supplying current to said ignition device and a thermostatic device in circuit adapted to be influenced by predetermined current values to 100 automatically alter the operative condition of said circuit and means for manually operating said thermostatic device to effect such 105 alteration in circuit condition.

3. In apparatus of the character described, in combination, an ignition circuit terminal, a battery circuit terminal, contacts connecting therewith, one of which contacts is 110 adapted to have a thermostatic action, movable contact means cooperative with the first said contacts to control the circuit condition of said terminals, and means cooperative with the contact having the thermostatic 115 action, adapted to cause said contact while serving as a conductor to also serve as a latch to hold the contacts in closed circuit position.

4. In apparatus of the character described, in combination, an ignition circuit terminal, a generator circuit terminal and a battery circuit terminal, separable contacts for closing and opening circuits through said terminals, one of said contacts being a conductor 120 of resilient material having a thermostatic characteristic, adapted to act to latch the contacts in closed circuit position and operate thermostatically to unlatch said contacts.

5. In apparatus of the character described, the combination with a storage battery, generator and ignition devices, and electric circuits therefor, of a controlling switch for said circuits comprising a manually operable carrier having contacts, fixed contacts adapted to be engaged by certain of said carrier contacts, and a spring conductor serving to contact with another carrier contact and latch the carrier in contact engaging position, said conductor having a thermostatic characteristic adapted to cause it to move to unlatching position under the influence of abnormal current values. 10
- 15 6. In apparatus of the character described, the combination with a storage battery, generator and ignition devices, and electric circuits therefor, of a controlling switch for said circuits comprising a manually operable carrier having contacts, fixed contacts adapted to be engaged by certain of said carrier contacts, and a spring conductor serving to contact with another carrier contact and latch the carrier in contact engaging position, said conductor having a thermostatic characteristic adapted to cause it to move automatically to open circuiting and unlatching position under the influence of abnormal current values. 20
- 25 7. In apparatus of the character described, the combination with a storage battery, ignition devices, and electric circuits therefor, of a controlling switch for said circuits comprising a contact carrier, a fixed contact adapted to be engaged by one of the carrier contacts, and a resilient conductor member, having a thermostatic characteristic, said conducting member being arranged to flex into position to latch the carrier in contact engaging position and adapted under the influence of certain current values to flex into unlatching position. 30
- 35 8. In apparatus of the character described, in combination, a series of terminals, a resilient contact connected to one of said terminals, another resilient contact for connecting a pair of said terminals, a starting circuit including the first said contact, generator and ignition circuits closed through said second contact, a contact carrier member, a spring for urging said member into contact disengaging position, means for manually urging said carrier against said spring to temporarily close a circuit 40
- 45 through the first said resilient contact and move the second said contact to open circuit position, a storage battery, and a thermostat in circuit therewith, said thermostat being yieldable out of the path of said carrier and adapted to snap into latching relation with said carrier to hold same in running position against the action of said spring, and said thermostat being adapted to be influenced out of latching relation by current 50
- 55 flow from said battery. 60
5. In apparatus of the character described, in combination, a series of terminals, a resilient contact connected to one of said terminals, another resilient contact for connecting a pair of said terminals, a starting circuit including the first said contact, generator and ignition circuits closed through said second contact, a contact carrier member, a spring for urging said member into contact disengaging position, means for manually urging said carrier against said spring to temporarily close a circuit 65
- 70 through the first said resilient contact and move the second said contact to open circuit position, a storage battery, and a thermostat in circuit therewith, said thermostat being yieldable out of the path of said carrier and adapted to snap into latching relation with said carrier to hold same in running position against the action of said spring, and said thermostat being adapted to be influenced out of latching relation by current 75
- 80 flow from said battery. 80
9. In apparatus of the character described, in combination, a series of terminals, a resilient contact connected to one of said terminals, another resilient contact for connecting a pair of said terminals, a starting circuit including the first said contact, generator and ignition circuits closed through said second contact, a contact carrier member, a spring for urging said member into contact disengaging position, means for manually urging said carrier against said spring to temporarily close a circuit through the first said resilient contact and move the second said contact to open circuit position, a storage battery, a thermostat in circuit therewith, said thermostat being yieldable out of the path of said carrier and adapted to snap into latching relation with said carrier to hold same in running position against the action of said spring, and said thermostat being adapted to be influenced out of latching relation by current 85
- 90 flow from said battery, and a manually operable member connected to said thermostat whereby the latter may be moved manually to unlatching position. 90
10. In a switch for the electrical system of internal combustion engines, in combination, a carrier having a plurality of contacts, a base having a plurality of contacts, contacts of the base and carrier being normally disengaged by a spring urging the carrier away from the base, means for moving said carrier into contact engaging position, and a thermostatic conductor member having a free contacting end adapted to engage with contact means on said carrier when the latter is moved, said conductor member serving thereafter to prevent full return of the carrier, and said conductor member being adapted to move under the influence of higher than normal current values to automatically release the carrier. 95
11. A switch comprising in combination terminals for starting, battery, generator, and ignition circuits, contacts for said terminals, a carrier having means for opening and closing the circuits through said terminals, and a coiled thermostatic conductor having a free contacting end, said conductor being of spring material adapted to permit the carrier to ride by and then snap into latching relation with said carrier preventing its full return. 110
12. A switch comprising in combination terminals for starting, battery, generator and ignition circuits, contacts for said terminals, a carrier having means for opening and closing the circuits through said terminals, and a coiled thermostatic conductor having a free contacting end, said conductor being of spring material adapted to permit the carrier to ride by and then snap into latching relation with said carrier preventing its full return, and means manually op- 115
- 120
- 125
- 130

erable for disengaging the carrier and conductor.

13. In apparatus of the character described, in combination, an engine starting motor, a magnetic starting switch, a storage battery for supplying current to said magnetic switch and to said motor, an ignition device adapted to receive current from said battery during the starting operation, a generator adapted to be included in a circuit with the ignition device and battery to supply current for the ignition device and recharge the battery when the engine is running, and a controlling switch for the aforesaid devices comprising a casing, a base having a plurality of terminals and contacts fixed thereto, a reciprocatory contact carrier, spring urged in said casing away from contact engaging relation with the contacts of said terminals, a nose on said carrier, means for moving said carrier to close a circuit through said battery including said starting switch and said ignition device, the nose on said carrier operating to open a circuit including said generator and said ignition device, and means for holding the carrier in "running position" against the action of its spring permitting deenergization of the magnetic switch and the inclusion of the generator in circuit with the battery and ignition device.

14. In apparatus of the character described, in combination, an engine starting motor, a magnetic starting switch, a storage battery for supplying current to said magnetic switch and to said motor, an ignition device adapted to receive current from said battery during the starting operation, a generator adapted to be included in a circuit with the ignition device and battery to supply current for the ignition device and recharge the battery when the engine is running, and a controlling switch for the aforesaid devices comprising a casing, a base having a plurality of terminals and contacts fixed thereto, a reciprocatory contact carrier spring urged in said casing away from contact engaging relation with the contacts of said terminals, a nose on said carrier, means for moving said carrier to close a circuit through said battery including said starting switch and said ignition device, the nose on said carrier operating to open a circuit including said generator and said ignition device, means for holding the carrier in "running position" against the action of its spring permitting deenergization of the magnetic switch and the inclusion of the

generator in circuit with the battery and ignition device, and means for manually operating said last means to release said carrier to the action of its spring. 60

15. In apparatus of the character described, in combination, an engine starting motor, a magnetic starting switch, a storage battery for supplying current to said magnetic switch and to said motor, an ignition device adapted to receive current from said battery during the starting operation, a generator adapted to be included in a circuit with the ignition device and battery to supply current for the ignition device and recharge the battery when the engine is running, and a controlling switch for the aforesaid devices comprising a casing, a base having a plurality of terminals and contacts fixed thereto, a reciprocatory contact carrier spring urged in said casing away from contact engaging relation with the contacts of said terminals, a nose on said carrier, means for moving said carrier to close a circuit through said battery including said starting switch and said ignition device, the nose on said carrier operating to open a circuit including said generator and said ignition device, and means for holding the carrier in "running position" against the action of its spring permitting deenergization of the magnetic switch and the inclusion of the generator in circuit with the battery and ignition device, said holding means comprising an electric conductor of resilient material having a thermostatic characteristic and a free contacting end, the same adapted to be included in circuit with said battery and thermostatically movable to release the carrier to the full action of its spring when abnormal current values obtain in certain of said circuits. 75 80 85 90 95

16. In apparatus of the character described, in combination, a carrier having a plurality of contacts movable therewith, a plurality of fixed contacts communicating with starting, generating and ignition circuits, means adapted to open the generator circuit while a contact of said carrier engages the fixed starting contact, means for returning said carrier to disengage it from certain of said fixed contacts, and a thermostatic conductor associated with one of said fixed contacts adapted to serve as a latch to hold the carrier in "running position." 100 105 110

Signed at Boston, in the county of Suffolk and State of Massachusetts, this 28th day of February A. D. 1917.

WILLIAM B. MOSES.
